WATER CLOSET

Clarence H. Johnson, Chicago, Ill., assignor to
 Pullman-Standard Car Manufacturing Company,
 Chicago, Ill., a corporation of Delaware

Application September 9, 1939, Serial No. 294,045

20 Claims. (Cl. 4—85)

This invention relates to water closets for railway cars involving the use of an upper dumping pan and a bottom closure member with operating mechanism therefor designed to effect full closing of the bottom closure member before initiating the dumping action of the upper pan and the return movements of such members in reverse sequence, whereby the initial opening movement of the bottom closure member is delayed until the upper dumping pan is restored to fully closed, normal position.

The invention also contemplates the restoration of the flushing mechanism for the water closet to its normal, non-flushing condition in the event that the upper pan is prevented from returning to normal, closed position, or the bottom closure member either to normally open or closed position, or both members affected simultaneously by an obstruction in the closet, thereby to prevent draining of the water supply tank.

The principal object of the invention is to provide a compact operating mechanism having lost motion mechanism between the upper pan and the bottom closure member adapted to afford sequential operation of such members in the order desired.

Specifically, the invention has for its object the provision of a rack and pinion mechanism adapted to afford lost motion to effect the actuation of the bottom closure member prior to actuation of the upper pan and lost motion adapted to provide for continued movement of the mechanism after the bottom member is actuated to effect the actuation of the upper pan.

The foregoing and other and more specific objects of the invention are attained by the mechanism illustrated in the accompanying drawings, in which—

Fig. 1 is a plan view of the hopper and operating mechanism with parts broken away better to show the flushing valve operating arrangement;

Fig. 2 is a side elevational view of the hopper with the operating mechanism in normal position with the upper pan closed and the bottom closure member open;

Fig. 3 is a similar view of the hopper with the mechanism operated to a point where both the upper pan and the bottom closure member are disposed in fully closed position;

Fig. 4 is still another side elevational view of the hopper with the mechanism further operated to its final, extreme position of movement with the upper pan in the fully open or

dumping position and the bottom closure member still fully closed and from which position the parts then assume the position illustrated in Fig. 2, in which position the lower chamber is permitted to empty;

Fig. 5 is a vertical sectional view through the center of the hopper taken on the line 5—5 of Fig. 1 with the operating parts in normal position and illustrating the hopper construction;

Fig. 6 is a vertical, transverse, sectional view through the center of the hopper, taken on the line 6—6 of Fig. 2, with the parts in normal position and further illustrating the hopper construction;

Fig. 7 is an enlarged, fragmentary, sectional view of the upper pan shaft mounting and mechanism and the bottom closure member mounting;

Fig. 8 is a sectional view through the intermediate operating shaft taken on the line 8—8 of Fig. 7 and showing the spiral spring arrangement for providing a lost motion connection between the upper pan and the bottom closure member;

Fig. 9 is a sectional view through the upper pan shaft taken on the line 9—9 of Fig. 7 and showing the spiral spring arrangement for urging the upper pan toward closed position;

Fig. 10 is a detail, perspective view of the operating rack;

Fig. 11 is a detail, perspective view of the upper pan, operating shaft and pinion and the counterbalancing spring;

Fig. 12 is a detail, perspective view of the bottom closure member, lost-motion spring and counterbalance; and

Fig. 13 is a detail, perspective view of the rack-engaging, intermediate pinion.

In the drawings, 10 represents a water closet constructed in accordance with the invention and including the base member 11 having outwardly extending bottom flange 12 which may be reinforced, if desired, by ring member 13 to prevent distortion thereof when secured to uneven supporting surfaces. The base tapers upwardly, as at 14, to a point intermediate the height of the water closet where it is provided with a vertically disposed flange 15 continuous about the perimeter and having a horizontal top surface. A chute member 17 is disposed within the base member 11 and secured at the position of the vertical flange 15 by welding. The chute is tapered downwardly to a bottom opening and is provided with a recess 18 in the rearmost wall for a purpose hereinafter to appear. The flange 15, with

the top edge of the chute 17, provides a throat into which housing member 16 is received and adapted to be secured by welding—one series of continuous spot welds securing the three thicknesses of metal comprising the flange 15, the chute 17 and the housing member 16. Above the point of attachment to the flange 15 and the chute member, the rear wall 19 of the member 16 extends substantially vertically, while the respective side walls 20 flare outwardly above that point, and the front wall 21 is also flared, to a substantially greater degree, to provide an extended front. The side walls 20 are each provided with a recess 22 having a horizontally disposed top surface perforated at 23 for a purpose hereinafter to be described. At the top, the housing member 16 is provided with an outwardly extending flange 24 continuous about the upper edge and disposed on a horizontal plane to provide a seat. The housing member 16 and the base member 11, together with the chute 17, all integrally secured together, comprise the stand portion of the water closet. The base and chute members are each of them formed from a single, integral piece of metal drawn to the desired shape, but the housing member is developed from a single blank of metal, of the desired contour, having a vertically disposed, interlocking, welded seam 34 in the rear wall and pressed to the required shape. The horizontal seat afforded by the top flange 24 on the housing member 16 is embraced by a sealing gasket 25 which may be of rubber, if desired, or any other suitable material.

Seated upon the gasket 25 is the bowl 26 of the water closet having the horizontally disposed shelf portion 27 complementary to and supported from the seat afforded on the stand. The bowl is provided with an extended front corresponding to that of the stand and, from the shelf portion 27 inside the stand, tapers down to a discharge opening emptying into the chute 17. From the shelf 27 upwardly, the bowl extends vertically a short distance, as at 28, and then is provided with an inwardly extending flange 29 to provide the rim 30. The rim is provided with the elongated opening 31 having curved edges, as at 32, and is provided with an overhanging portion 33 at the rear for the support of mechanism presently to be described. At opposite sides, in positions complementing the recesses 22 in the respective side walls of the stand, the bowl is provided with projections 35 integral with the sides of the bowl and adapted to receive bolts 36 entered through the openings 23 in the top surface of the recess 22 securely to retain the bowl 26 in proper sealing relation to the stand.

Flushing mechanism 45 is provided for the water closet and is supported wholly from the bowl and rim structure, as best shown in Figs. 1 and 5. A supporting bracket 46 is secured to the overhanging rim structure 33 by means of seat hinge bolts 47 and is formed with depending flanges 48 disposed at opposite sides to provide spaced bearings for the reception of the hollow operating shaft 49. An operating lever 50 is pressed onto one end of the shaft 49 and secured by a pin 39 and bears against one side of one of the depending flanges 48, thereby to prevent displacement of the shaft with respect to the flange in one direction. A bifurcated actuating cam 51 is securely anchored on the operating shaft at the opposite side of the depending flange referred to by means of set screw 52 and serves to prevent movement of the shaft in the opposite direction, where by axial displacement thereof is

positively prevented. The bifurcated jaws of the cam 51 are adapted to engage the ball-shaped end 53 of bell-crank lever 54 which is pivoted on integral stud 55 depending from the underside 5 of the supporting bracket 46 and the bifurcated arm 56 of which engages the operating plunger 57 of the flushing valve 58 to change the rotary motion of the cam 51 into a horizontal thrust on the valve plunger when the operating lever 50 is actuated. The free end of the plunger 57 finds bearing in a flanged bracket member 59 secured to the flushing valve 58 by means of screws taking the studs 60 integral therewith. The bifurcated arm 56 of the bell-crank 54 engages bearing block 61 on the plunger 57 in order to actuate that member.

The flushing valve 58 is mounted from flange 63 depending from the rear of the supporting bracket 46 by means of securing nuts taking integral studs 64 on the valve body. The valve is connected to a source of water supply, at 65, and communicates with the interior of the closet bowl 26 by means of an intervening T-shaped member 66 secured to the bowl at 67 and to which the flushing valve is connected at 68. The T member 66 is provided with one spout 69 adapted to direct flushing water into the area of the rim of the bowl on the shelf 27 and another spout 70 adapted to direct water in the same direction into the bowl 26, whereby an effective whirling action of the water is set up thoroughly to flush the closet. A tray 71, supported at its free end from one of the studs 64 by means of the securing nut, extends beneath the flushing valve 58 to collect any moisture dripping therefrom and drains into the closet stand as at 72. A top cover plate 39, secured by screw 38, conceals the mechanism from view. The flushing mechanism is actuated coincidentally with the operation of operating mechanism for the upper dumping pan and bottom closure member, as hereinafter described, by means of treadle 74 fulcrumed intermediate its ends at 41 on fulcrum bracket 73—here shown as supported directly from the floor independently of the closet stand.

One end of the treadle 74 is pivotally connected, at 42, with a strut 44 which, in turn, is pivotally connected, at 43, to the flushing mechanism operating lever 50, whereby, upon depression of the foot-engaging portion of the treadle, causing an upward thrust on the strut 44, the shaft 49 will be rotated to cause the cam 51 to actuate the bell-crank 54, thereby to press the plunger 57 of the flushing valve and flush the closet. The location of the fulcrum 73 with respect to the ratio of the length of the lever 74 upon opposite sides thereof, together with the height of the fulcrum above the floor, will, of course, determine the length of travel of the operating parts; and bodily shifting of the fulcrum and treadle lever fore and aft, thereby increasing the angle of the strut 44, will determine the range of operation—all in accordance with requirements of the various flushing valves differing slightly in dimension and operation. A resilient bumper 40 is disposed on the underside of the treadle at the foot-engaging portion to prevent metallic contact with the floor or supporting surface and serves as a limit of movement for the operating mechanism. The treadle mechanism is used as a gauge in initially installing the arrangement. When it is desired to locate the fulcrum bracket 73, the strut 44 is secured to

the valve operating lever 50 by the connection 43 and the treadle 74 then pivoted about the fulcrum 73 to a position with the bumper 40 contacting the floor. The bracket 73, with the lever 74, is then shifted to a position where the maximum range of operation of the particular flushing valve is obtained, and secured. By disconnecting the drip tray 71 and the connection 43 and a connection 139 to the operating mechanism, it will be seen that the entire flushing mechanism can be removed with the bowl 26, from which it is wholly supported, without disturbing any of the other mechanism.

An upper dumping pan 75 is provided which, in the normal position, is adapted to seal the discharge opening 80 from the closet bowl 26; and a bottom closure member 85 is provided which, in its closed position, is adapted to seal the bottom drain opening 90 from the chute 17. The upper pan is insulated, as at 76, the insulation being enclosed by outer shell 71. The dumping pan 75 is actuated by means of the hollow upper shaft 81 to which the pan is anchored by means of attaching bracket 78 through the medium of set screws 79. The shaft 81 is pivotally carried in spaced bearing members 82 and 83 disposed adjacent opposite ends thereof and separate from but fixedly secured in the respective side walls 20 of the closet stand immediately above the joinder of the base 11 with the chute 17 and housing member 16 by means of similar nuts 84 clamping the side walls between similar shoulders 86, on the respective bearings, and the nuts. The bearing 83 is provided with an outwardly disposed seat 87 upon which a torsional spring 88 is mounted and the inner end of which is anchored thereto by flange 89 entered in slot 99. The outer end of the spring is connected by rebent flange 91, through slot 101, to circumferential flange 92 of disk 93 enclosing the spring and having integral hub 94 securely anchored to the shaft 81 by means of set screw 95 for rotation therewith. The tension on the spring 88 may readily be adjusted merely by winding up the spring by means of the member 93 to the desired degree before setting the screw 95. The amount of spring tension necessary is determined solely by the force required to counterbalance the dumping pan 75 in closed position. Thus, it will be seen that since the bearing 83 of which the spring seat 87 is an integral part is rigidly fixed the spring 88 will exert a force on the member 93 tending to rotate the shaft 81; and by the direction of the coils of the spring, it will be noted that this force is exerted to rotate the shaft in a direction to urge the dumping pan towards fully closed position against limit stop 96 where it is normally maintained. Disc washer 97, seated against collar 98 on the bearing 83, encloses the inner side of the spring 88.

The bottom closure member 85 is provided with spaced stub shafts or trunnions 102 offset from the plane of such member, whereby the axis of operation is disposed above the floor line and the bottom member therebeneath and by means of which the member is pivotally mounted in spaced bearing members 103 and 109 separate from but fixedly secured in the respective side walls of the base member 11 by means of similar nuts 104 clamping such side walls between shoulders 105, on the respective bearings, and the nuts. The bearing 109 is provided with a bottom base flange 110 seated on flange 12 of

the closet base 11 and a web 111 extending upwardly for a purpose hereinafter to appear and having an inwardly directed top flange 112 bearing against the side wall of the base 11. A counterweight 106 is securely anchored to the outer end of one of the stub shafts 102 by means of set screw 107 in a position tending to urge the bottom closure member 85 toward open position where it is normally held. A resilient bumper 108 is disposed on the underside of the counterweight to deaden the sound of operation and comes in contact with bottom flange 12 of the base 11 to limit the opening movement of the member 85. While the side walls of the housing 16 and the base 11, in which the shafts 81 and 102, respectively, are mounted, are disposed at an angle to such shafts, it will be noted, as best shown in Fig. 7, that such walls are provided with parallel portions at right angles to the axes 20 of the respective shafts for attachment of the shaft bearing members 82, 83, 103 and 109.

The operating mechanism for the dumping pan 75 and the bottom closure member 85 is designed for sequential operation of those members and coincidentally with the flushing operation, with the bottom closure member first coming fully closed against the chute opening 90 before the dumping pan begins to move away from its seat against stop 96 to expose the discharge opening 80. The bottom closure member 85 is operated directly from the treadle 74 through mechanism including the strut 44 and separately from the dumping pan 75. The stub shaft 102, extending through the bearing 109, is provided on its exposed end with a segmental pinion 120 fixedly secured thereto by set screw 121 and having gear teeth 122 by means of which the bottom member 85 may be actuated. The teeth 122 are disposed in constant mesh with complementary gear teeth 123 on an intermediate pinion assembly 124 mounted upon an outwardly extending, intermediate shaft 113 secured to the web 111 by means of an integral, smaller diameter, countersunk end rivet portion 114. The pinion 124 is an assembly comprised of the hollow cylinder 128, having integral hub 126 coextensive with and having bearing 119 pivotally mounted on the shaft 113, and a complementary operating member 125 having bearing 118 pivotally mounted with respect to the member 128 on the hub 126 thereof and having an extended hub 132 entered within the cylinder 128, together with an intervening torsional spring 127. The torsional spring is disposed 50 within the hollow cylinder 128 about the hub 132 and anchored at its outer end to the perimeter of the cylinder by means of rebent flange 131 engageable with shoulder 130 formed by the gear segment 129. At its inner end, the spring 127 is anchored to the hub 132 on operating member 125 by means of flange 134 entered within slot 133.

The operating member 125 is provided with an integral, laterally extending lug 135 projecting into the path of movement of the gear segment 129 and against which such segment normally bears under the influence of spring 127. The intermediate pinion assembly 124 provides a positive means of initially actuating the bottom closure member 85 to closed position and thereafter affords lost motion means to absorb the continued movement necessary to operation of the dumping pan 75, as will hereinafter appear. The cylinder 128, operating member 125

and the spring 127 may be assembled as a separate unit prior to mounting upon the intermediate shaft 113, and the spring may be adjusted to any desired degree of tension merely by relative rotation of the opposing parts in a direction to wind up the spring and thereby to cause the cylinder 128 with its integral gear segment 129, in operation, to move in unison with the operating member 125 to actuate the bottom closure member 85. The adjustment of the spring is maintained by the engagement of the segment 129 with the lug 135 under pressure of the spring. The cylinder 128, by means of hub 126, is mounted upon the shaft 113, freely, for relative rotation with respect thereto; and the operating member 125 is mounted upon the hub 126 for relative rotation therebetween, whereby the whole mechanism is disposed in floating relation to the intermediate shaft 113 which acts merely as the fixed axis for the pivotal operation thereof. The operating member 125 is provided with an annular bearing surface 146 having a segmental portion containing gear teeth 147 disposed within the outer circumference of the annular bearing and adapted to co-operate with a rack 148 having an opening 149 of a width closely to receive the operating member and engage the annular bearing 146. The opening 149, on one side, is provided with gear teeth 150 projecting into the opening and adapted constantly to mesh with the inset teeth 147 on the operating member, as best shown in Figs. 2, 3 and 4. The close engagement between the rack opening 149 and the annular bearing 146 maintains the gear teeth 150 and 147 in constant mesh. The rack 148 is held in operative engagement with the operating member 125 by means of a disk washer 145 secured in place by a slotted-head screw 144 threaded into the exposed end of the intermediate shaft 113. By means of the screw and disk 144 and 145, the pinion assembly 124 is also maintained in operative association and upon the shaft 113 against a bearing embossment on the web 111. An integral disk 151 on the operating member prevents the spring 127 from escaping from the cylinder 128.

The rack 148, and therefore the operating member 125, is actuated directly from the treadle 74 and, for this purpose, is provided with an integral, vertically projecting lug 136 by means of which the rack may be operated through the medium of a connecting link 137 extending between the lug 136, to which it is pivotally secured by fastening means 138, and the flushing mechanism operating lever 50, to which it is pivotally secured by fastening means 139 and which is operated directly by the strut 44 from the treadle 74, whereby the link 137 provides a means of operating the rack and the operating member 125 coincidentally with the flushing mechanism upon depression of the treadle 74. The connecting link, where it associates with the fastening means 139 on the lever 50, is provided with a slot 143 for a purpose hereinafter to appear. Thus, it will be seen that upon actuation of the treadle the initial movement causes the bottom closure member 85 immediately to assume its fully closed position in sealing relation to the drain opening 90 from the chute 17. The immediate response of the bottom closure member to the flushing action occurs prior to any movement whatever of the upper dumping pan 75 and is necessary to prevent the possibility of a draft from the opening 90 through the discharge

opening 80 as would occur if the upper pan opened before or during the raising or lowering movements of the bottom closure member; and, during this initial movement, the operating member 125 and the cylinder 128 move in unison as though they were a single, integral member. The rack 148 is designed also to operate the dumping pan 75 and for this purpose is provided with a second opening 152 for co-operation with a segmental pinion 140 fixedly secured on the upper pan shaft 81 by means of a set screw 142 threaded through the bearing hub 141. The pinion 140 is similar to the operating member 125 in that it is provided with an annular bearing 153 having gear teeth 154 disposed within the outer circumference thereof and adapted to be closely received within the opening 152, with the gear teeth in operative association with complementary gear teeth 170 projecting from one side of the opening and meshing with the teeth 154, after the bottom closure member 85 has reached its sealing position with respect to opening 90 and upon continued movement of the operating parts, thereby to rotate the shaft 81 and dump the pan 75 which empties into the chute 17 as the pan enters the recess 18 provided in the rear wall of the chute for that purpose. The rack 148 is maintained in co-operative relation with the pinion 140 by means of a disk washer 172 secured to the shaft 81 by a slotted screw 173 threaded into a bushing 174 sweated into the end of the hollow pan shaft. The close engagement between the walls of the opening 152 and the annular bearing 153 maintains the proper relation therebetween for engagement of the gear teeth 170 and 154.

During the continued movement of the operating parts necessary to operate the dumping pan after the bottom closure member 85 reaches its final position, the cylinder 128, with its segment 129 for operating the bottom closure member, remains fixed in the final position of movement to close such member, while the operating member 125 continues to rotate relatively thereto under the influence of the rack teeth 150 in mesh with the teeth 147 and against the increasing tension of the torsional spring 127 as the lug 135 moves away from the segment 129, at which time the spring is wound more tightly during such relative rotation of the parts and, upon release of the operating pressure, unwinds again to the point where the lug 135 regains contact with the segment 129. The gear teeth 170 on the rack are out of mesh with the teeth 154 on the upper shaft pinion 140 when the parts are in their normal position with the pan 75 closed and the member 85 open and do not engage such teeth until after the bottom closure member has reached its sealing position beneath opening 90 by reason of the fact that, while gear teeth 150 are continuous along one side of rack opening 149 to provide constant engagement with pinion 124, the gear teeth 170 extend only a portion of the distance along one side of rack opening 152—leaving a space 171 which must be traversed before the first tooth on the rack engages the teeth 154 on the pinion 140 to operate the pan 75.

The sequential operation of the mechanism in its various progressive positions assumed during the flushing period is best depicted in Figs. 2, 3 and 4. In Fig. 2, all of the parts, including the flushing mechanism, are shown in their normal position of rest with the dumping pan 75 fully closed and the bottom closure member 85

fully open. The segment 129 is seated against the lug 135, and the rack teeth 170 are spaced from the upper pan pinion teeth 154 with the rack teeth 159 in constant mesh with the intermediate pinion teeth 147 and the gear teeth 122 and 123 on the bottom closure member and cylinder 128, respectively, of course in constant mesh. When it is desired to flush the closet, it is necessary merely to step upon the treadle 74 which pivots about the fulcrum 73 to exert an upward thrust on the strut 44 and thereby actuate the lever 50 to operate the flushing valve 58 by means of the cam 51 and bell-crank 56. The pan 75 and member 85 are operated sequentially by the treadle 74 and strut 44 coincidentally with the operation of the flushing mechanism by reason of the operative connection 137 between the rack 148 and the lever 50. Therefore, the same upward thrust of the strut 44 causes the connecting link 137 to raise the rack 148 and thereby rotate the operating member 125 in a direction to cause the gear segment 123 on cylinder 128, through the medium of spring 127, to rotate the pinion gear segment 120 and move the bottom closure member 85 into sealing relation with opening 90 by means of the engagement between gear teeth 123 and 122, as shown in Fig. 3. During this initial movement, the pan 75 has not moved from its closed position in sealing relation with the discharge opening 80, but the rack 148 has moved to a position where the teeth 170 will engage the pinion teeth 154 immediately after the member 85 reaches closed position. As shown in Fig. 3, it will be seen that both the dump pan 75 and bottom closure member 85 are in fully closed position, while contact with the pinion teeth 154 has not yet been made by the rack teeth 170; but the segment 129 on cylinder 128 is still in engagement with the lug 135. When the engagement between the rack teeth 170 and pinion teeth 154 occurs, a positive, direct operating connection is made between the treadle mechanism and shaft 81, thereby to dump the pan 75.

Contact between the segment 129 and lug 135 is maintained during the initial movement by spring 127 up to that point in the operation when the member 85 contacts the chute 17, thus acting rigidly to close the bottom closure member; and when that point is reached, the lug 135 moves away from the segment 129 as the rack teeth 170 engage the pinion teeth 154 to rotate the shaft 81 and dump the pan 75 upon continued movement of the rack 148 under influence of the treadle mechanism—thus acting flexibly to afford the continued movement to open the dump pan. During such continued movement, the pinion segment 129 remains in its final position of rotation in closing the member 85, while the spring 127 compensates for the relative rotation between the parts 125 and 128; and the tension thereon is gradually increased as the operating member 125 is rotated by the rack 148 during the dumping of the pan 75. The final dumping position of the upper pan 75 is illustrated in Fig. 4, at which time the pan enters the recess 18 provided therefor in the rear wall of chute 17 while the bottom closure member 85 remains in sealing relation to chute opening 90. In this figure, it will be noted that the pinion segment 129 is still in its final position of movement, while the operating member 125 has been rotated by the rack 148 to its final position with the lug 135 spaced from the segment 129 and the gear teeth 170 fully meshed with the

pinion teeth 154 in the final position of the pinion 140 with the spring 127 wound up to its greatest degree of tension under normal conditions. The treadle 74 has moved to its extreme position with the bumper 40 bearing against the floor, and the flushing mechanism has attained full flushing force—sending water through the nozzles 68 and 70 into the bowl 26 to be drained through discharge opening 80 into the chute chamber 17, after which, when treadle 74 is released all of the operating parts are restored to their normal position in directly reverse sequence with the pan 75 first closing completely under influence of its spring 88 before the bottom closure member 85 under influence of counterweight 106 and the weight of material in chute 17 is opened to release the contents from the chute 17 through opening 90, at which time the parts have again assumed the position shown in Fig. 2.

While the dumping operation of the pan 75 and the initial operation of the bottom closure member 85 takes place coincidentally with the operation of the flushing mechanism, the release of each mechanism is accomplished independently of the other; and the speed with which the flushing mechanism returns to non-flushing condition is not dependent upon or affected by the time required for the dump pan and bottom closure member operating parts to return to normal position after the pressure has been released from treadle 74. By means of slot 143 in the connecting link 137 at the connection 139 to the lever 50 in combination with the floating type mounting of the intermediate pinion assembly 124, the flushing mechanism is adapted to return to non-flushing condition even though the operating parts for the pan 75 and the bottom closure member 85 might, for some reason, be prevented from returning to their normal position of rest, whereby continuous operation of the flushing valve and consequent draining of the water supply tank (not shown) is prevented. It will be seen that by reason of the floating connection of the operating member 125, that member, after having been operated to its extreme position of movement in dumping the pan 75, will return at least to a position where the lug 135 will contact the gear segment 129 under the influence of spring 127; and in the event that the member 85 for some reason is prevented from opening, that position will be as shown in Fig. 3 with the pinion cylinder 128 prevented from returning fully to its normal position of rest by the engagement between the gears 122 and 123. With the operating member 125 having reached this position, the flushing mechanism then may return to fully released, non-flushing position by reason of the slotted engagement 143 of the connecting link 137 with the connection 139 on the lever 50. Even though both the bottom closure member 85 and the dump pan 75 be prevented from returning to their respective normal positions—i. e., the member 85 prevented from opening and the pan 75 prevented from closing, the flushing mechanism will be released as above described. By having the floating type mounting of the intermediate pinion assembly 124 and the loose connection between the upper pan shaft pinion 140 and the rack 148, the dump pan 75 may remain in any position, because of an obstruction, without affecting the return of the flushing mechanism to released position. The pan 75 may be pressed open with a hose or the like for cleaning

purposes, against the resistance offered by the balancing spring 88, without operating either the bottom closure member 85 or the flushing mechanism; and, likewise, the bottom closure member 85 may be swung through its complete arc of travel or obstructed at any point without affecting the operation of either the pan 75 or the flushing mechanism. In the event that the bottom closure member 85 should become obstructed and fail to close, the compensating action of the spring 127 will still permit dumping of the pan 75 and operation of the flushing mechanism.

It is to be noted that while the springs 88 and 127 are wound up simultaneously in the operation of the pan 75, they do not function in opposition one to the other but operate separately—each performing its own function independently of the other.

It will be understood that the intermediate pinion assembly might be dispensed with and the lost-motion arrangement thereof incorporated directly in the lower pinion for association with the rack without departing from the invention.

From the foregoing, it will be seen that there has been provided a water closet and operating mechanism in which compensating action is provided for all possible conditions adversely affecting the operation of the mechanism, whereby the flushing mechanism is rendered operative at all times.

What is claimed is:

1. A water closet including a bowl having a discharge opening; a supporting stand having a drain opening; a dump pan operatively associated with said discharge opening and having an operating shaft; a bottom closure member operatively associated with said drain opening and having an operating shaft; and means for sequentially operating said closure member and dump pan comprising a pinion on said dump pan operating shaft, a pinion on said closure member operating shaft, an intermediate pinion co-operating with said last-named pinion, and an actuating rack co-operating with the first-named pinion and said intermediate pinion.

2. A water closet including a bowl having a discharge opening; a supporting stand having a drain opening; a dump pan operatively associated with said discharge opening and having an operating shaft; a bottom closure member operatively associated with said drain opening and having an operating shaft; and means for sequentially operating said closure member and dump pan comprising a pinion on said dump pan operating shaft, a pinion on said closure member operating shaft, an intermediate pinion co-operating with said last-named pinion, an actuating rack co-operating with the first-named pinion and said intermediate pinion, and a lost-motion spring mechanism associated with one of said pinions.

3. A water closet including a bowl having a discharge opening; a supporting stand having a drain opening; a dump pan operatively associated with said discharge opening and having an operating shaft; a bottom closure member operatively associated with said drain opening and having an operating shaft; and means for sequentially operating said closure member and dump pan comprising a pinion on each of said operating shafts, an intermediate pinion co-operating with one of said pinions, and an actuating rack co-operating with the other of said pinions and said intermediate pinion, and a lost motion

spring mechanism associated with one of said pinions.

4. A water closet including a bowl having a discharge opening; a supporting stand having a drain opening; a dump pan operatively associated with said discharge opening and having an operating shaft; a bottom closure member operatively associated with said drain opening and having an operating shaft; and means for sequentially operating said closure member and dump pan comprising a pinion on said dump pan operating shaft, a pinion on said closure member operating shaft, an intermediate pinion co-operating with said last-named pinion, and an actuating rack co-operating with the first-named pinion and said intermediate pinion, said intermediate pinion comprising independent gear segments engageable with said rack and second-named pinion respectively and connected by a spring for relative pivotal movement.

5. A water closet including a bowl having a discharge opening; a supporting stand having a drain opening; a dump pan operatively associated with said discharge opening and having an operating shaft; a bottom closure member operatively associated with said drain opening and having an operating shaft; and means for sequentially operating said closure member and dump pan comprising a pinion on each of said operating shafts, an intermediate pinion co-operating with one of said operating shaft pinions, and an actuating rack co-operating with the other of said operating shaft pinions and said intermediate pinion, one of the pinions comprising independent gear segments connected by means of a spring for relative pivotal movement.

6. A water closet including a bowl having a discharge opening; a supporting stand having a drain opening; a dump pan operatively associated with said discharge opening and having an operating shaft; a bottom closure member operatively associated with said drain opening and having an operating shaft; and means for sequentially operating said closure member and dump pan comprising a pinion on each of said operating shafts, an intermediate pinion co-operating with one of said pinions, and an actuating rack co-operating with the other of said pinions and said intermediate pinion.

7. A water closet including a bowl having a discharge opening; a supporting stand having a drain opening; a dump pan operatively associated with said discharge opening and having an operating shaft; a bottom closure member operatively associated with said drain opening and having an operating shaft; and means for sequentially operating said closure member and dump pan comprising a pinion on said dump pan operating shaft, a pinion on said closure member operating shaft, an intermediate pinion co-operating with said last-named pinion, an actuating rack co-operating with the first-named pinion and said intermediate pinion, and lost motion means between said rack and first-named pinion for movement of said dump pan independently of said rack.

8. A water closet including a bowl having a discharge opening; a supporting stand having a drain opening; a dump pan operatively associated with said discharge opening and having an operating shaft; a bottom closure member operatively associated with said drain opening and having an operating shaft; and means for sequentially operating said closure member and dump pan comprising a pinion on said dump pan

operating shaft, a pinion on said closure member operating shaft, an intermediate pinion co-operating with said last-named pinion, an actuating rack co-operating with the first-named pinion and said intermediate pinion, and lost-motion means between said rack and first-named pinion, said intermediate pinion comprising independent gear segments engageable with said rack and second-named pinion respectively and connected by means of a spring for relative pivotal movement.

9. A water closet including a bowl having a discharge opening; a supporting stand having a drain opening; flushing mechanism; a pan operatively associated with said discharge opening and having an operating shaft; a bottom closure member operatively associated with said drain opening and having an operating shaft; and means for sequentially operating said closure member and dump pan comprising a pinion on said dump pan operating shaft, a pinion on said closure member operating shaft, an intermediate pinion co-operating with one of said pinions, an actuating rack co-operating with the other of said pinions and said intermediate pinion, and means for actuating said rack coincidentally with said flushing mechanism.

10. A water closet including a bowl having a discharge opening; a supporting stand having a drain opening; flushing mechanism; a dump pan operatively associated with said discharge opening and having an operating shaft; a bottom closure member operatively associated with said drain opening and having an operating shaft; and means for sequentially operating said closure member and dump pan comprising a pinion on said dump pan operating shaft, a pinion on said closure member operating shaft, an intermediate pinion co-operating with one of said pinions, an actuating rack co-operating with the other of said pinions and said intermediate pinion, a lost-motion connection between the rack and said flushing mechanism, and means for actuating said rack coincidentally with said flushing mechanism.

11. A water closet including a bowl having a discharge opening; a supporting stand having a drain opening; a dump pan operatively associated with said discharge opening and having an operating shaft; a bottom closure member operatively associated with said drain opening and having an operating shaft; and means for sequentially operating said closure member and dump pan comprising a pinion on said dump pan operating shaft, a pinion on said closure member operating shaft, a rack co-operating with said pinions, lost-motion means between said rack and first-named pinion for movement of said dump pan independently of said rack, and lost-motion means between said rack and second-named pinion for movement of the bottom closure member independently of the dump pan.

12. A water closet including a bowl having a discharge opening, a supporting stand having a drain opening, a dump pan operatively associated with said discharge opening and having an operating shaft, a bottom closure member operatively associated with said drain opening and having an operating shaft, a pinion on each of said operating shafts, an intermediate pinion assembly in constant mesh with one of said first-named pinions, and a rack member in constant mesh with said assembly and associated with but normally out of mesh with the other of said first-named pinions, said intermediate pinion assem-

bly comprising independent gear segments connected by a torsional spring for relative pivotal movement.

13. A water closet including a bowl having a discharge opening, a supporting stand having a drain opening, a dump pan operatively associated with said discharge opening and having an operating shaft, a bottom closure member operatively associated with said drum opening and having an operating shaft, a pinion on each of said operating shafts, an intermediate pinion in constant mesh with one of said first-named pinions, a rack member in constant mesh with said intermediate pinion and associated with but normally out of mesh with the other of said first-named pinions, and lost motion means for movement of the rack after the bottom closure member is closed.

14. A water closet having a bowl provided with a discharge opening; a supporting stand having a drain opening, a dump pan adapted normally to seal said discharge opening; a bottom closure member for association with said drain opening; and means for operating said bottom closure member and dump pan comprising rack-and-pinon mechanism having a lost-motion connection with the dump pan affording delayed action thereof.

15. A water closet having a bowl provided with a discharge opening; a supporting stand having a drain opening; a dump pan adapted normally to seal said discharge opening; a bottom closure member for association with said drain opening; and means for operating said bottom closure member and dump pan comprising rack-and-pinon mechanism having a loose connection with the dump pan adapted to afford movement thereof independently of such mechanism.

16. A water closet having a bowl provided with a discharge opening; a supporting stand having a drain opening; a dump pan adapted normally to seal said discharge opening; a bottom closure member for association with said drain opening; and means for operating said bottom closure member and dump pan comprising rack-and-pinon mechanism having lost-motion connection with the bottom closure member adapted to afford movement of the bottom closure member independently of such mechanism.

17. A water closet having a bowl provided with a discharge opening; a supporting stand having a drain opening; a dump pan adapted normally to seal said discharge opening; a bottom closure member for association with said drain opening; and means for operating said bottom closure member and dump pan comprising rack-and-pinon mechanism having a lost-motion connection with the dump pan affording delayed action thereof and adapted to afford movement of the dump pan independently of the mechanism, and a lost-motion connection with the bottom closure member affording movement thereof independently of said mechanism.

18. A water closet having a bowl provided with a discharge opening; a supporting stand having a drain opening; a dump pan adapted normally to seal said discharge opening and having an operating shaft; a bottom closure member for association with said drain opening and having an operating shaft; a pinion on each of said shafts; and means for operating said bottom closure member and dump pan comprising a rack member engageable with said pinions and having a lost-motion connection with the dump pan pinion affording delayed action of said dump

pan and adapted to afford movement of the dump pan independently thereof.

19. A water closet having a bowl provided with a discharge opening; a supporting stand having a drain opening; a dump pan adapted normally to seal said discharge opening and having an operating shaft; a bottom closure member for association with said drain opening and having an operating shaft; a pinion associated with each of said shafts; and means for operating said bottom closure member and dump pan comprising a rack member engageable with said pinions, said pinion associated with the bottom closure member including lost-motion means affording movement of such member independently of said operating means. 15

20. A water closet having a bowl provided with a discharge opening; a supporting stand having a drain opening; a dump pan adapted normally to seal said discharge opening and having an operating shaft; a bottom closure member for association with said drain opening and having an operating shaft; a pinion associated with each of said shafts; and means for operating said bottom closure member and dump pan comprising a rack member engageable with said pinions, said pinion associated with the bottom closure member including lost-motion means affording movement of said operating means independently of said member.

CLARENCE H. JOHNSON.

CERTIFICATE OF CORRECTION.

Patent No. 2,258,454.

October 7, 1941.

CLARENCE H. JOHNSON.

It is hereby certified that error appears in the printed specification of the above numbered patent requiring correction as follows: Page 2, first column, line 75, for "where by" read --whereby--; page 4, first column, line 5, for "opposiing" read --opposing--; page 6, first column, line 50, claim 2, for "dain" read --drain--; page 7, first column, line 14, claim 9, before "pan" insert the word --dump--; and second column, line 9, claim 13, for "drum" read --drain--; and that the said Letters Patent should be read with this correction therein that the same may conform to the record of the case in the Patent Office.

Signed and sealed this 9th day of December, A. D. 1941.

(Seal)

Henry Van Arsdale,
Acting Commissioner of Patents.
